WEATHER STRIP

Frank Reese, Excelsior, Minn., assignor to Reese Metal Weather Strip Co., Minneapolis, Minn., a corporation of Minnesota

Application March 17, 1941, Serial No. 383,717

5 Claims.

(Cl. 20—69)

My invention relates generally to improvements in weather-strips and particularly to weather-stripping for the sides of double-hung windows.

In the conventional double-hung window, the upper and lower sashes are installed in a window frame with considerable clearance between the stiles of the sashes and the side members of the frame. The terminals of the customary beveled portions of the sash meeting rails are rabbeted to accommodate their respective portions of the parting beads of the window frame, the rabbets being relatively deep to provide clearance between the meeting rails and the edges of the parting beads of substantially the same clearance as that existing between the stiles of the sashes and the side members of the frame. These clearances are desirable to allow for contraction and expansion and for irregularities in construction to the end that the sashes will slide freely in the frame. The companion rabbets in corresponding ends of the adjoined meeting rails of the upper and lower sashes form a groove which gaps more or less between the back wall of said groove and the opposing edge of the parting bead accommodated therein, it being desirable, of course, to obstruct this gap so that when the sashes are shut, the window structure will be tight at the ends of the meeting rails. Window structures have been equipped with pads of felt, commonly called dust pads, separately tacked or otherwise separately fastened directly to the parting beads at the level occupied by the adjoined meeting rails of the shut sashes. A pad of this kind, so located, plugs the gap between the edge of its respective parting bead and the back wall of the rabbeted meeting rail groove.

My present invention contemplates the provision of weather-stripping equipment for application to window frames along the parting beads thereof and along the adjacent portions of the window sashes, such equipment having plugs or stoppers associated therewith to render the window structures completely weather-tight, an object of the invention being to provide such weather-stripping equipment of highly efficient character and of simple, durable and relatively inexpensive construction in which meeting rail plugs or stoppers may be readily incorporated at the weather-strip factory or elsewhere and which with such dust plugs or stoppers associated therewith may be readily applied to window frames and sashes at the sash factory or building site by non-skilled workmen.

With the foregoing and other objects in view, which will appear in the following description, the

invention resides in the novel combination and arrangement of parts and in the details of construction hereinafter described and claimed.

In the drawings, Fig. 1 is a fragmentary horizontal sectional view of one side of a double-hung window structure in which the sashes are shut, said view showing a side member of the frame with its parting bead together with adjacent portions of the meeting rails of the sashes, and showing also my improved weather-stripping applied to such structure; Fig. 2 is a fragmentary view partly in elevation and partly in section, the section being taken as on the line 2—2 of Fig. 1 and said view representing the window structure as seen from the inside thereof with the lower sash removed; Fig. 3 is a fragmentary view partly in elevation and partly in section, the section being taken as on the line 3—3 of Fig. 1 and said view representing the window structure as seen from the outside thereof with the upper sash removed; Fig. 4 is a fragmentary view of the window structure shown in Figs. 1-3, said view showing in vertical section portions of the upper and lower sashes and showing in elevation a portion of the side member of the frame together with its parting bead and my improved weather-stripping applied thereto and to said sashes; Fig. 5 is a fragmentary perspective view illustrating the lower portion of the upper frame strip section; Fig. 6 is a fragmentary vertical sectional view in detail illustrating the weather strip portion shown in Fig. 5 and additionally illustrating a dust plug or stopper associated therewith; Fig. 7 is a detail sectional view taken on the line 7—7 of Fig. 6; Fig. 8 is a perspective view in detail of the filler-piece in the stopper construction shown in Fig. 6, and Fig. 9 is a perspective view in detail of the stopper strip employed in fastening said filler-piece to the frame strip.

Reference being had to the accompanying drawings, wherein similar parts are designated by similar reference characters, it will be seen that the principal views fragmentarily illustrate one side of a conventional double-hung window structure and particularly those parts of such structure in proximity to the level wherein the meeting rails of the upper and lower sashes come together when the sashes are shut.

The window frame A includes a side jamb 10, inner and outer stops 11, 12 and a parting bead 13 set in a groove 14 in said jamb 10. Slidably mounted in the window frame A between the parting bead 13 and outer stop 12 is an upper window sash 15 having a meeting rail 16 at the bottom thereof and similarly mounted in said

frame A between said parting bead 13 and the inner stop 11 is a lower sash 17 having a meeting rail 16 at the top thereof. Said meeting rails 16 of said sashes 15, 17 have the usual oppositely beveled meeting portions 18 formed at their ends with rabbets 19, each accommodating its respective portion of the parting bead 13 and each having a sidewall 20 spaced from its adjacent side of said bead and also an end-wall 21 spaced from the edge of said bead 13, the side wall 20 lying flush with the corresponding face of the sash stile 22.

The parting bead 13 is formed in upper and lower sections abutting each other end to end approximately at the center line of the adjoined meeting rails 16.

The weather stripping illustrated in embodiment of the present invention includes a frame strip comprising upper and lower frame strip sections B, B', sash strips C for the upper and lower sashes 15, 17 and a dust plug or stopper D associated with said upper frame strip section B. Each of the frame strip sections B, B' consists of a length of sheet metal longitudinally bent to form a web 23, legs 24 and flanges 25, said web 23 and legs 24 providing an outwardly opening channel 26 embracing the parting bead 13 and said legs 24 and flanges 25 providing inwardly opening channels 27 at opposite sides of said bead 13. The lower end of the upper section B and the upper end of the lower section B' of the frame strip meet at a level slightly beneath the meeting plane of the upper and lower sections of the parting bead 13 and both sections are secured to said parting bead by means of screws 28 extending through the webs 23 of said sections and threaded into said bead 13. Each sash strip C consists of a length of sheet metal longitudinally bent to form an attaching lip 29, a leg 30 disposed at right angles to said lip, and a flange 31 turned back from said leg into spaced parallelism with respect thereto. Said lip 29 is suitably fastened to a sash along the edge of its stile with the leg 30 extending along the face of the stile and into and along the side-wall 20 of the rabbet in the meeting rail 16. In this disposition of a sash strip C, the leg 30 and flange 31 thereof provide an outwardly opening channel 32 which slidably interlockingly receives the corresponding flanges 25 of the frame strip sections B, B', said flange 31 of said sash strip C being at the same time similarly received in the inwardly opening channel 27 of said frame strip sections formed by the corresponding frame strip flanges 25 and the companion leg 24.

The web 23 of the upper frame strip section B is formed with a transverse slot 33 therein near the lower end thereof and between said end of said strip and said slot, said web is further formed with protuberances 34 struck outwardly therefrom.

The dust plug or stopper D includes a metallic strip 35 transversely bent to provide an upright intermediate guide portion 36, upper and lower cam portions 37 in continuation of said guide portion and symmetrically inclined therefrom, coplanar shoulders 38 in continuation of said cam portions 37 disposed in a plane offset from the plane of said guide portion 36, and reduced terminal portions or clips 39 turned back from said shoulders 38. The upper clip 39 of the stopper strip 35 is threaded through the slot 33 in the web 23 of the upper frame strip section B and is clinched behind said web, while the lower clip 39 of said stopper strip is clinched about the lower

edge of said web 23. Clipped to the frame strip section B in this manner, said stopper strip 35 is secured thereto with said shoulders 38 planted against the web 23. The width of the stopper strip 35 and the offsetting of the guide portion 36 thereof relative to the shoulders 38 are proportioned relative to the gap in the rabbet-formed groove of the adjoined meeting rail 16, the width of said strip approximating the distance between the flanges 31 of the sash strips C and the extent of the offset of the guide portion 36 from the shoulders 38 approximating the distance between the web 23 of the frame strip section B and the back wall of said rabbet-formed groove. Thus, the transversely bent stopper strip 35 in itself effectually obstructs the gap in said groove, when the sashes are shut, and together with the frame strip section B and sash strip C renders the window structure substantially weather tight.

The cam portions 37 of the stopper strip 35 facilitates the final shifting of the sashes 15 in shutting the same, the upper cam portion 37 co-operating with the meeting rail 16 of the lower sash to center the same in the window frame and the lower cam portion 37 likewise co-operating with the meeting rail 16 of the upper sash. In addition to the stopper strip 35, I prefer in most cases to employ a thin pad 40 of felt or a similar filler-piece of oblong rectangular formation which is backed flatwise against the web 23 of the frame strip section B and tied in place in such position by the stopper strip 35 with the outwardly punched protuberances 34 of said web piercing the material of the pad. In such disposition of such pad or filler-piece 40, the upper cam portion 37 of the stopper strip 35 overreaches the upper edge of said filler-piece while the lower cam portion 37 of said stopper strip 35 underreaches the lower edge of said filler-piece. This pad or filler-piece 40 is slightly wider than the stopper strip 35 and its side edges are slidably engaged by the flanges 31 of their respective sash strips C. Thus, the combination of said stopper strip 35 and pad 40 affords an effective sealing obstruction in the gap in the rabbet-formed groove of the adjoined meeting rails 16 having no appreciable interference with the usual opening and closing movements of the window sashes.

The provision in sectional form of the parting bead 13 and of the frame stripping is preferred to facilitate the application of the window sashes 15, 17 to and the removal thereof from the window frame A, and in thus providing said frame strip sections B, B', the application to the section B of the lower end of the stopper strip 35 is simplified in requiring only the clinching of the lower clip 39 about the lower edge of the web 23 of said section B.

From the foregoing, it will be readily comprehended that the gap-obstructing plugs or stoppers of the present invention may be conveniently applied to upper strip sections of the frame stripping at the weather strip factory, sash mill or building site and that applied to such upper strip sections, said plugs or stoppers, without further attention, will assume their proper places upon the application of the weather strips to a window structure.

Changes in the specific form of my invention, as herein disclosed, may be made within the scope of what is claimed without departing from the spirit of my invention.

Having described my invention, what I claim

as new and desire to protect by Letters Patent
is:

1. Weather stripping for a side of a double-hung window with sashes having rabbets in their meeting rails conforming with their respective portions of the parting bead of the window frame and forming, in the adjoined relationship of said rails, a gapping groove loosely receiving the parting bead, said weather stripping consisting of a frame strip comprising upper and lower sections adjoined end to end at the level of the adjoined meeting rails and extending along the parting bead, each of said frame strip sections including a web overlying the edge of said bead, the upper frame strip section having protuberances at its lower portion struck outwardly from the web thereof and having a transverse slot formed in said web above said protuberances, sash strips, one for each of the sashes, each sash strip interlockingly cooperating with said frame sections and extending along the stile of its respective sash and the side wall of the rabbet in the meeting rail thereof, a stopper for plugging the gap in said rabbet-formed meeting rail groove, said stopper comprising a filler-pad backed against said lower portion of the web of the upper frame strip section and its outwardly struck protuberances, and an upright tie-strip embracing said filler-pad and securing the same to said frame strip, the upper portion of said tie-strip being terminally caught in said slot in said web of the upper frame strip section and downwardly inclined to overreach the upper edge of said filler-pad for cam-like coaction with the lower sash, and the lower portion of said tie-strip being terminally caught about the lower edge of said web of said upper frame strip section and inclined to underreach the lower edge of the filler-pad for cam-like coaction with the upper sash.

2. Weather stripping for a side of a double-hung window with sashes having rabbets in their meeting rails conforming with their respective portions of the parting bead of the window frame and forming, in the adjoined relationship of said rails, a gapping groove loosely receiving the parting bead, said weather stripping consisting of a frame strip comprising upper and lower sections adjoined end to end at the level of the adjoined meeting rails and extending along the parting bead, each of said frame strip sections including a web overlying the edge of said bead, the upper frame strip section having a transverse slot formed in said web, sash strips, one for each of the sashes, each sash strip interlockingly cooperating with said frame sections and extending along the stile of its respective sash and the side wall of the rabbet in the meeting rail thereof, a stopper for plugging the gap in said rabbet-formed meeting rail groove, said stopper comprising a filler-pad backed against said lower portion of the web of the upper frame strip section and an upright tie-strip embracing said filler-pad and securing the same to said frame strip, the upper portion of said tie-strip being terminally caught in said slot in said web of the upper frame strip section and the lower portion of said tie-strip being terminally caught about the lower edge of said web of said upper frame strip section.

3. Weather stripping for a side of a double-hung window with sashes having rabbets in their meeting rails conforming with their respective portions of the parting bead of the window frame and forming, in the adjoined relationship of

5 said rails, a gapping groove loosely receiving the parting bead, said weather stripping consisting of a frame strip extending along the parting bead and including a web overlying the edge of said bead, sash strips, one for each of the sashes, each sash strip cooperating with said frame strip and extending along the stile of its respective sash and the side wall of the rabbet in the meeting rail thereof, a stopper for plugging the gap in said rabbet-formed meeting rail groove, said stopper comprising a filler-pad, backed against the web of the frame strip and an upright tie-strip embracing said filler-pad and securing the same to said frame strip, the upper portion of said tie-strip being fastened at its terminal to said web of the frame strip and downwardly inclined to overreach the upper edge of said filler-pad for cam-like coaction with the lower sash, and the lower portion of said tie-strip being fastened at its terminal to said web and upwardly inclined to underreach the lower edge of the filler-pad for cam-like coaction with the upper sash, the intermediate portion of said tie-strip extending along the face of the filler-pad and lying adjacent to the back wall of said rabbet formed meeting rail groove, each side edge of said filler-pad being slidably contacted by its respective sash strip.

4. Weather stripping for a side of a double-hung window having a frame, sashes, and a parting bead on said frame for the sashes, said sashes having rabbets in their meeting rails conforming with their respective portions of the parting bead and forming, in the adjoined relationship of said rails, a gapping groove loosely receiving the parting bead, said weather stripping consisting of a frame strip comprising upper and lower sections disposed end to end in adjoining relationship at the level of the adjoined meeting rails and extending along the parting bead, sash strips, one for each of the sashes, each sash strip cooperating with said frame sections and extending along the stile of its respective sash and the side wall of the rabbet in the meeting rail thereof, a stopper cooperating with said sash strips and with the back walls of said rabbets to plug the gap in said meeting rail groove, said stopper comprising a filler-pad mounted on the upper frame strip section at the lower portion thereof adjacent the adjoining upper end of said lower frame strip section.

5. Weather stripping for a side of a double-hung window having a frame, sashes, and a parting bead on said frame for the sashes, said sashes having rabbets in their meeting rails conforming with their respective portions of the parting bead and forming, in the adjoined relationship of said rails, a gapping groove loosely receiving the parting bead, said weather stripping consisting of a frame strip comprising upper and lower sections disposed end to end in adjoining relationship at the level of the adjoined meeting rails and extending along the parting bead, sash strips, one for each of the sashes, each sash strip cooperating with said frame sections and extending along the stile of its respective sash and the side wall of the rabbet in the meeting rail thereof, a stopper cooperating with said sash strips and with the back walls of said rabbets to plug the gap in said meeting rail groove, said stopper being mounted on one of said frame strip sections at the end portion thereof adjoining the other of said sections.
